(57) CLAIM

The ornamental design for a carrying case, as shown and described.

DESCRIPTION

FIG. 1 is a front perspective view of a carrying case; FIG. 2 is a front elevation view of the carrying case of FIG. 1; FIG. 3 is a rear elevation view of the carrying case of FIG. 1; FIG. 4 is a left side elevation view of the carrying case of FIG. 1;

FIG. 5 is a right side elevation view of the carrying case of FIG. 1;
